UNITED STATES PATENT OFFICE.

CARLO TURCHI, OF FERRARA, ITALY.

APPARATUS FOR THE SIMULTANEOUS TRANSMISSION OF TELEPHONIC AND TELEGRAPHIC CURRENTS OVER THE SAME LINE.

No. 801,936.

Specification of Letters Patent.

Patented Oct. 17, 1905.

Application filed July 13, 1904. Serial No. 216,374.

To all whom it may concern:

Be it known that I, CARLO TURCHI, engineer, a subject of the King of Italy, and a resident of Ferrara, in the Kingdom of Italy, have invented certain new and useful Improvements in Apparatus for the Simultaneous Transmission of Telephonic and Telegraphic Currents Over the Same Line; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to enable a "double metallic" telephone-line (*i. e.* a telephone-line composed of a wire for the outgoing and a second parallel wire for the return current) to be used effectively and advantageously as a conductor for the simultaneous transmission of a telephonic current with another current, hereinafter called the "superimposed current," without interference between the two currents. The superimposed current may be a telephonic, telegraphic, or high-potential continuous or alternating current. Some solutions of this problem have already been given by Ducoussو, Pierard, Caihlo, Swensky, Barret, Jacob, and Gaunt; but my present invention provides a new solution and is able to obviate many important practical difficulties presented more or less by the above solutions.

Figure 1 is a diagrammatic view showing the ordinary system for the transmission of simultaneous telephonic and telegraphic messages over the same line. Fig. 2 is a diagrammatic view of a portion of my system. Fig. 3 is a longitudinal section through my separator-coil. Fig. 4 is a diagrammatic view showing a plurality of telephonic systems on a single metallic circuit.

In order to enable this invention to be clearly understood, I shall first proceed to describe its theoretical basis, which is common to the art, with reference to the diagram shown by Fig. 1 of the accompanying drawings. In this figure, A B and C D are the two line-wires of a telephonic line with complete metallic circuit, and T' and T² are the two telephonic terminals. The points A D at one end of the line are connected to the conductor M H, and the points B and C at the other end

are connected to the conductor N K. The 55 conductors M H and N K are earthed at their ends H and K. P, situated between H and M, represents a generator of current—telephonic, telegraphic, or high-potential continuous or alternating current—and Q, situated between K and N represents an apparatus for receiving the current, which will reach the said receiving apparatus through the two wires of the telephonic line in parallel. In general a portion of the superimposed current will pass through the telephones T' and T² and produce in them noises having a more or less unfavorable influence on the efficient transmission of spoken messages. In order to obviate such unfavorable influence, earlier inventors have proposed to make the resistances of the branches M A M D equal and also to make the resistances of the branches B N and C N equal. By these means the electrical potential is rendered equal at the points A D, 70 and therefore no portion of the current generated at P will flow through the branch A D and through the telephone T'. Moreover, if the resistances of the two wires A B C D are the same no portion of the said current will 75 pass through the branch B C and the telephone T². Furthermore, the circuit A M D is open to the telephonic current generated at the telephonic station T'; but the resistances of the branches A M and D M being equal 80 no portion of the telephonic current will pass through the conductor M P to earth, and likewise, for the same reason, no portion of the telephonic current will flow through the conductor N Q to earth.

According to the foregoing general principle a double telephonic or the other line can be employed theoretically as a single conductor for a superimposed current without interference between the two currents; but 95 in practice the arrangement as described with reference to Fig. 1 presents many weak points. First, the two wires of the telephonic line never have exactly the same ohmic resistances, or if their ohmic resistances are exactly 100 the same their respective impedances are not equal; second, the branches A M D and B N C act as short circuits for the telephonic current, and thus considerably diminish the loudness of the transmitted voice.

Earlier inventors proposed various ways of providing the branches A M, M D, B N, C N with resistances in order to reduce so far as

possible the amount of the short-circuiting of the telephonic current through the branches A M D and B N C. One inventor proposed an arrangement in which the impedances of 5 the two telephonic lines were made as far as possible equal to each other; but the introduction of resistance in the branches A M, D M, B N, and C N necessarily diminished the strength of the superimposed current. 10 Then some inventors proposed an inductive arrangement by which the resistance of the said branches to the superimposed current was practically unaltered, while the resistance to the short-circuiting of the telephonic current 15 was very much increased.

Having thus explained the theoretical basis (which is common to the art) of this invention, I shall now proceed to set forth the practical disadvantages of the previously-proposed 20 systems.

The first point to be considered when a telephonic line with metallic return is to be employed for a simultaneous superimposed-current service is that there should not be the 25 slightest loss in the telephonic current. Therefore the resistance of the branches A M D B N C should be practically equal to the insulation resistances.

Second. The introduction of such resistances in the branches A M, D M, B N, C N should not cause the least loss in the superimposed current, especially if the latter is a 30 telephonic current.

Third. The impedances of the two telephonic 35 lines, as above stated, must be made equal, which they very seldom are in reality. Therefore the system must be provided with means for regulating the said impedances, and in order not to alter the resistance of the wires 40 A B and C D, and thus produce a loss in the telephonic current, such means must be provided in the branches A M, D M, B N, C N.

Fourth. The electrostatic capacity between the branches A M and M D or B N and C N 45 must be practically *nil*, in which respect the earlier systems have been chiefly deficient. Obviously the short-circuiting of the telephonic current may take place not only through the ohmic resistances of the branches 50 A M D and B N C, but also through the said electrostatic capacity, which in certain arrangements of the above-described system is very great and is sufficient to cause a great loss of telephonic current.

Having so set forth the principal objects 55 which the present invention must realize in order to completely solve the problem, I shall now explain the manner in which the said problem is solved by the present invention.

Fig. 2 illustrates diagrammatically an 60 installation at one end or station of the system carried out in accordance with my present invention, and it is to be understood that a similar installation must be placed at the other 65 end or station of the system. Further, in

this figure the invention is assumed to be applied to a superimposed telegraph service, but only by way of example. In fact, any other superimposed current may be employed. Referring now to the said figure, P is the 70 Morse station, T' the receiving-telephone, m the microphone provided with its battery p and its transformer t. The two branches M A and M D are wound on one and the same soft-iron core in the following way to form a 75 "separator-coil." The two branches are wound together for the greater part of their length, the remainder of the length of each being wound as a separate coil. Thus M A first is wound alone for a length a b on the 80 core S T, and then it is wound as to its remainder c d on the same core together with the branch M D, as shown more clearly in Fig. 3. Similarly, a portion e f of the branch M D is wound alone, and the remainder g h 85 is wound together with M A.

So far as possible the coils a b and e f must be equal. The coils c d and g h being wound together are always exactly equal. Furthermore, the two branches M A and M D are 90 wound in opposite directions, so that they have a differential action on the core S T.

The separate or additional coils or windings 95 of the respective branches need not necessarily be made as a whole with the main winding, as described and shown, but they may be separate therefrom.

The ohmic resistances of the branches M A M D are exactly equal, and their inductances are made exactly equal by a very simple arrangement of regulation. The length of the core S T is shown exactly equal to the distance 100 a f, so that if, for instance, the inductance of the branch M A should be greater than the inductance of the branch M D the core S T 105 must be shifted by suitable means, such as a screw, to the right. As the inductance of the branch M D does not change while the inductance of the branch M A is lessened, it is

obvious that the two inductances can be made 110 exactly equal. The core S T might be made shorter than the distance a f—for instance, as indicated by the dotted lines x y in Fig. 3—in which case by acting by its movement in opposite way on the two branches the regulation 115 will be rendered more delicate. Thus by this means of regulation the impedances of the two branches A M D M are rendered exactly equal. If now a telegraphic current is generated by the apparatus P, this current 120 will divide in two parts, each of which will flow through one of the branches, as indicated by the black arrows, and as the impedances of the two branches are made equal and the branches are wound in opposite direction, the 125 self-inductance introduced in the telegraphic circuit by the above system will be exactly *nil*, so that the only alteration in the telegraphic circuit will consist in the increase of the ohmic resistance, which will be equal to 130

one-half of the ohmic resistance of one of the branches. Thus whatever telegraphic system—simplex or duplex or quadruplex—may be used its speed will never be reduced.

5 The result of regulating the branches A M D M, as above described, so as to obtain the same potential at the points A and D is that no portion of the telegraph-current will flow through the branch A D and the telephone T' 10 will be silent.

The case of a telephonic current flowing through the telephonic circuit will now be considered. It is assumed that the telephonic current is produced by the microphone *m* and 15 passes through the transformer *t* to the branch A D, and thus to the line. A portion of this current will flow through the branch A M D; but as the impedances of the branches A M D M are equal no telephonic current will go 20 to earth through M P H. The direction of the current in the derivation A M D, as indicated by the dotted arrows, is such that the inductances of the two branches are added together, and as the mutual inductance between 25 the two branches is practically equal to the self-inductance of one of them, according to the construction of the coil, it can be assumed that the current will flow through a circuit the inductance of which is four times the inductance of one of the branches.

Now since, as above stated, the inductances of the two branches neutralize each other with respect to the superimposed circuit, there will be no difficulty in selecting the self-inductance of each branch in such a way that the four times greater inductance which the current finds in the circuit A M D will act practically as an insulation resistance, so that the loss of the telephonic current through the 40 shunt-circuit is thus rendered practically *nil*.

Expressed in figures, the improved apparatus offers to the telephonic current in the circuit A M D an impedance of about three hundred and twenty thousand ohms, while only 45 an additional resistance of eighty ohms is offered to the superimposed telegraphic current.

In order to prevent loss due to the circumstance that the electrostatic capacity between the two branches may be great enough to allow 50 a considerable portion of the current to pass from one branch to the other, the coil is wound as shown in Fig. 3, which shows the two additional small coils *a b e f*, used for the regulating device, wound in separate places 55 *a' b' e' f'* and the coils *c d g h* wound together in the central part of the coil *h k*.

The wire of the branch A M is represented by white circles and the wire of the branch D M by hatched circles.

60 In the figure the wires of the two branches are shown alternating in each row. Care is also taken that under a convolution of the wire of one branch there is situated a convolution of the wire of the other branch. The 65 electrostatic capacity between the two

branches could exist in two ways: first, by considering each horizontal row as a face of a cylindrical condenser, and, second, by considering each section of the coil normal to the axis as a face of a flat condenser. Now if 70 the number of the convolutions in each row is even it is clear that, considering, for instance, the two rows *p p' q q'*, each face of such a condenser is neutral, and if also the number of the rows is even the total capacity of the horizontal rows is *nil*. Similarly, if two sections, such as *m m' n n'*, be considered, the number of the rows being even, then both faces of such a condenser will be neutral, and therefore, the number of the convolutions being even, 80 the total capacity of the sections will be also *nil*. Therefore there will be no loss whatever of the telephonic current, while any rapid telegraphic system may be used as the superimposed circuit.

If, as is usually the case, the impedances of the two wires of the telephonic line are not equal, they may be made equal by the regulation of the impedances of the branches M A M D and there will be no loss of telephonic current 90 through M H to earth, because of the high impedance of the derivation A M D, as above set forth.

This invention may be applied to various purposes: first, for superimposed telegraphic, 95 telephonic, or high-potential currents; second, for combined telephone-circuits, which problem is too well known to need description; third, in combination with a system of simultaneous telephony and telegraphy, the apparatus for which can be included in the conductors M H and N K, thus giving three superimposed electrical communications. If the telephone-line in any of such cases is divided in various branches, each of them must be 100 provided at each end with such a separator-coil in the manner shown in diagram in Fig. 4. In this figure the telephone-line is shown divided in three sections, at each end of 105 which are placed the separator-coils *A^a A^b A^c A^d A^e A^f*. The telephonic stations are represented by *T^a T^b T^c T^d T^e T^f*. The current produced by the generator P will first flow through the telephonic section *T^a T^b*, and as the separator-coils must be regulated no disturbances will be produced in the telephones of said section. Then, if the vertex N of the separator of the end B of the first section is connected to the vertex R of the separator of the end C of the second section, the superimposed current will flow through the second 115 telephonic section in a similar manner without disturbing the telephones *T^c T^d*, and similarly the third telephonic section will be connected through the conductor S T, thus the 120 superimposed current reaching the receiving apparatus Q without having given any rise to disturbances in the telephones of the three sections, which will remain quite independent 125 one from the other.

One could easily understand how to proceed if instead of having three telephonic sections their number would have been four, five, or any number.

5 Having thus described my invention, what I claim as new, and desire to secure by Letters Patent of the United States of America, is—

10 1. In a superimposed telegraph and telephone system, the combination with a "double-metallic" telephone-line and its telephonic apparatus, of a "separator-coil" bridged across the two line-wires, comprising two coils of equal inductance wound together in opposite directions on the same core, and a telegraph branch circuit with telegraphic apparatus leading from a point of the separator-coil chosen between its two coils, the separator-coil being so constructed as to present no inductive resistance to the telegraph-current and an extremely high impedance to the telephone-current, as hereinbefore described.

15 2. In a superimposed telegraph and telephone system, the combination with a "double-metallic" telephone-line and its telephonic apparatus, of a "separator-coil" comprising two branches coiled together and separately on the same core, the inductances of the two branches being made equal by means of regulation, and a telegraph branch circuit and its telegraphic apparatus leading to earth from a point of the separator-coil chosen between its two branches, the separator-coil being so constructed as to present no inductive resistance to the telegraphic current and an extremely high impedance to the telephone-current, as hereinbefore described.

20 3. In a superimposed telegraph and telephone system, the combination with a "double-metallic" telephone-line and telephone apparatus, of a "separator-coil" bridged across the two line-wires, comprising two branches wound together in opposite directions on the same core, and two additional coils inserted in each one of the said branches, and a movable core, around which the two branches and the two additional coils are wound, the inductances of the two branches being made equal by suitably adjusting the movable core, and a branch telegraph-circuit provided with a telegraph apparatus, leading to earth from a point of the separator-coil chosen between the two branches, the separator-coil being so constructed as to present no inductive resistance to the telegraphic current and an extremely high impedance to the telephone-current, as hereinbefore described.

25 4. In a superimposed telegraph and tele-

phone system the combination with a "double-metallic" telephone-line, and telephone apparatus, of a "separator" connected across 60 the two line-wires, comprising two branches wound together in opposite directions on the same core, in such a way that the electrostatic capacity between the two branches is *nil*, and two additional coils inserted in each one of the 65 branches, and a movable core, the latter and the additional coils forming a means of regulation by which the inductances of the two branches and of the two line-wires are made equal, and a branch telegraph-circuit with 70 telegraphic apparatus leading to earth from a point of the separator-coil chosen between the two branches, the separator-coil being so constructed and adjusted as to present no inductive resistance to the telegraphic current 75 and an extremely high impedance to the telephone-current as hereinbefore described.

5. In a superimposed telegraph and telephone system, the combination with a "double-metallic" telephone-line and its telephonic apparatus; of a separator-coil bridged across the two lines and comprising a core, and two branches wound together on the core into a coil with an even number of rows and an even 80 number of sections, the wires of the branches 85 alternating in each row and in each section; and a telegraph branch circuit with a telegraphic apparatus, leading from a point of the separator-coil between its two branches.

6. In a superimposed telegraph and telephone system, the combination with a double-metallic telephone-line and its telephone apparatus; of a separator-coil bridged across the two lines and comprising a movable core, and two branches wound together and separately about the movable core; and a telegraphic branch leading from a point between the two branches. 90

7. The combination with a plurality of double-metallic telephone main lines and their telephonic apparatuses; of a separator-coil bridged across each main line at both ends thereof and comprising a core, and two branches wound together about the core in opposite directions; and telephone branches 95 100 105 leading from a point between each branch of the separator.

The foregoing specification signed at Venice, Italy, this 7th day of June, 1904.

CARLO TURCHI.
